UNITED STATES PATENT OFFICE

107,490

DESIGN FOR A DRESS

David Rosenthal, New York, N. Y.

Application October 1, 1937, Serial No. 71,910

Term of patent 3½ years

To all whom it may concern:

Be it known that I, David Rosenthal, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the specific dress disclosed of the specific central seam extending from below the belt line to the bust line and having multi-stitched shirrings as shown.

I claim:

The ornamental design for a dress, substantially as shown and described.

DAVID ROSENTHAL.
